UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed April 18, 1922. Serial No. 555,054.

This invention relates to internal combustion engines and particularly to the valves and valve operating mechanism. The particular engine chosen to illustrate an embodiment of the invention is an airplane engine having steel cylinders and welded-on water jackets, but the application of the invention is not necessarily limited to this engine construction.

10 One of the objects of the invention is to provide a light but rigid and lasting valve operating mechanism for an internal combustion engine.

15 Another object is to provide a double armed rock shaft for simultaneously operating two of the motor valves and a single operating arm for said shaft arranged between its ends.

20 Another object is to provide an engine having two exhaust ports and elbows with valve operating means mounted above said elbows and having its operating rod extending downwardly between said elbows.

25 Another object is to provide an operating rod for rocker levers having a reinforced ferrule at its tip adapted to engage by line contact with an adjustable tappet carried by the rocker arm.

30 The above and other objects of my invention will be apparent from the following description wherein reference is made to the accompanying drawings illustrating a preferred embodiment of my invention, and wherein similar reference numerals designate similar parts throughout the several views.

In the drawings:—

Fig. 1 is a front elevation of one of the cylinders of an airplane engine equipped with my improved valve operating mechanism, parts being broken away and shown in section;

Fig. 2 is an enlarged detail view of the rocker lever and associated parts;

Fig. 3 is a detail plan view of the rocker lever;

Fig. 4 is a detail sectional view showing the mounting of the rocker lever;

Fig. 5 is a sectional view taken substantially on the line 5—5 of Fig. 3;

Fig. 6 is an enlarged section on the line 6—6 of Fig. 5;

Fig. 7 is a perspective view of one of the tappet bolts;

Fig. 8 is a horizontal sectional view substantially on the line 8—8 of Fig. 2; and

Fig. 9 is a section on the line 9—9 of Fig. 8.

Referring to the drawings, the numeral 5 designates a cylinder of an airplane or other internal combustion engine water jacketed as 60 at 40 and having a piston 6 and provided with inlet and exhaust elbows 7. Each cylinder 5 is preferably provided with a plurality of inlets and exhausts to permit the introduction of a full charge and the more rapid and 65 complete scavenging of the burnt gases. The inlet and exhaust ports in the elbows are controlled by valves 9 having stems 10 passing through guide sleeves 11 secured in the elbows and terminating at their upper ends 70 in flat hardened tips adapted to be engaged by inwardly extending arms 12 of rocker levers 13. A spring 14 mounted between discs 8 respectively carried by the valve stem 10 and guide sleeve 11 tends to normally 75 hold the valve 9 firmly against its seat and to return the valve to its seat whenever the pressure of the rocker arm 12 is removed (see Fig. 2).

Each of the elbows 7 is secured as by welding to the cylinder head and jacket and they extend in pairs at each side of the cylinder. Thus in Figs. 8 and 9 the elbows are shown as extending beyond the jacket 40 and in communication with branches of an inlet or 85 exhaust pipe 41. The connection is made between the elbow and branches by bolts 42 extending into brackets 17 welded or otherwise secured on the extensions of the elbows.

There is a rocker lever 13 for each pair of valves and as herein shown each is provided with a pair of valve-engaging arms 12 arranged adjacent the ends of an elongated fulcrum portion 43 adapted to provide an extended area in engagement with anti-friction 95 rollers 15 encircling a pin 16 mounted at its opposite ends in upward extensions of the supporting brackets 17 (see Figs. 4 and 9). Each end of the pin 16 is secured in the split upper end of its respective supporting bracket by clamping bolts 44. A grease cup 18 may be mounted in the fulcrum portion 43 of the rocker lever 13 to provide lubrication for the bearings 15, suitable guard discs 19 being provided at the ends of the fulcrum portion to prevent leakage of the lubricant.

Mounted substantially centrally of the fulcrum portion 43 of the rocker lever is an oper-

ating arm 20 adapted to extend in the opposite direction from the valve-engaging arms 12 and be engaged by a vertical operating rod 21. The operating rod 21 is preferably 5 constructed as a hollow tube having a hardened metal ferrule 22 welded or otherwise secured upon its opposite ends, the lower ferrule resting within the upwardly extending cup 23 adjustably mounted at the upper end 10 of the thrust rod 24, the lower extremity of which carries a roller 25 riding upon the periphery of the cam 26 fixed upon the valve-operating shaft 27. The valve-operating shafts for the inlet and exhaust valves may 15 be suitably geared to be rotated from the crank shaft of the engine in the usual or any desired manner. The upper ferrule 22 of the operating rod 21 is adapted to engage the lower face of a tappet bolt 28 mounted in the 20 operating arm 20, a guide cup 29 being preferably arranged under the head of the tappet substantially as shown in Fig. 2 to prevent accidental dislocation of the operating rod from its tappet. The tappet 28 is preferably formed with a rounded body portion 25 having its periphery flattened at one or more points, as at 30, and fits within an aperture 31 in the operating arm 20, having one or more straight sides adapted to co- 30 operate with the flattened portions of the tappet to prevent its rotation (see Figs. 5, 6 and 7). The head of the tappet 28 is provided with a cylindrically rounded lower face 32 adapted to engage by line contact with the 35 upper flat surface of the ferrule 22 of the operating rod. By virtue of this construction the head of the operating rod rocks with little or no wear on the tappet 28 of the rocker arm at all positions of the rocker lever. 40 A nut 33 is threaded upon the upper extremity of the tappet 28 and bears against the upper surface of the rocker arm 20, to secure the tappet 28 and guide cup 29 to the arm.

45 A similar tappet 28 but without the cup, is mounted in each of the valve-operating arms 12 of the rocker levers with their cylindrical head portions 32 engaging by line contact with the flat tip of the valve stems 10 (see Fig. 2).

50 The operation of my improved valve-operating mechanism is believed to be apparent. As the crank shaft of the engine is rotated the valve operating shafts 27 are rotated to bring the cams 26 thereof into position to raise the operating rods 21 of the inlet and exhaust valves, the cams 26 being properly positioned upon the shafts 27 to oscillate the rocker levers 13 at the desired times. The 55 upward movement of the operating rods 21 will swing upwardly the operating arm 20 of the rocker lever 13, causing a simultaneous downward swinging movement of both the valve-engaging arms 12 of the rocker lever 60 to open the valves 9 against the tension of

their springs 14. The valves 9 are thus held open until the cams 26 have revolved sufficiently to allow the operating rods 21 to drop to their normal positions, whereupon the springs 14 will return the valves to closed 70 positions and swing upwardly the valve-engaging arms 12 of the rocker lever with consequent lowering of the operating arm 20 and operating rod 21 to maintain the roller 25 in contact with the periphery of the cam 75 26. During the oscillation of the rocker lever 13, the cylindrically rounded faces of the tappets 28 will rock on the flat upper surfaces of the ferrule 22 of the operating rod and the valve stems 10, maintaining a rocking line contact with each of these members throughout their entire movement.

While it will be apparent that the illustrated embodiment of my invention herein disclosed is well-calculated to adequately fulfill the objects and advantages primarily stated, it is to be understood that the invention is susceptible to variation, modification and change within the spirit and scope of the subjoined claims.

Having thus described my invention, what I claim and desire to secure by Letters Patent is:

1. In an engine, a cylinder having a plurality of ports therein, valve arranged to normally close said ports, a rocker lever arranged to simultaneously open and close said valves, said rocker lever having an elongated fulcrum portion, a pair of valve-engaging arms normal to the ends of the fulcrum portion, and an operating arm normal to the fulcrum portion and extending centrally therefrom in the opposite direction from the valve-engaging arms.

2. In an engine, a cylinder having a plurality of ports therein, valves arranged to normally close said ports, a rocker lever arranged to simultaneously open and close said valves having a plurality of spaced parallel valve-engaging arms normal thereto and an operating arm arranged centrally of the valve-engaging arms and extending in the opposite direction.

3. In an engine, a cylinder having a plurality of ports therein, valves arranged to normally close said ports, a rocker lever arranged to simultaneously open and close said valves comprising an elongated fulcrum portion, a plurality of spaced valve-engaging arms, normal to the ends of the fulcrum portion an operating arm arranged centrally of the valve-engaging arms, and an operating rod engaging by line contact with said operating arm.

4. In an engine, a cylinder having a plurality of ports therein, valves arranged to normally close said ports, a rocker lever arranged to simultaneously open and close said valves and formed with a plurality of spaced valve-engaging arms and an operating arm

- arranged centrally of the valve-engaging arms, a tappet mounted in the operating arm and having an arcuate face, an operating rod having a hardened ferrule secured at its upper extremity and engaging by line contact with the arcuate face of said tappet, and a guide cup carried by the operating arm and encircling the operating rod.
5. A valve-operating rocker lever for engines having an elongated fulcrum portion, a plurality of spaced valve-engaging arms normal to the fulcrum portion, and a single operating arm normal to the fulcrum portion and centrally between the valve-engaging arms.
10. In an engine, in combination, a cylinder having a pair of valves and substantially parallel conduits extending laterally from said valves, supports upon the walls of said 20 conduits, a rocker lever mounted on said supports, arms on said lever to operate said valves, and an operating rod extending upwardly between said conduits for moving said rocker lever.
25. 7. In an engine, in combination, a cylinder having a pair of valves and substantially parallel conduits extending laterally from said valves, a rocker lever supported from said conduits having arms for operating said valves, and an operating rod extending upwardly between said conduits for moving said rocker lever.
8. A valve operating mechanism comprising an operating arm, a tappet therein having an arcuate face and secured against turning in the arm, a cup secured to said arm by said tappet, and an operating rod extending into said cup in contact with said face.
35. 9. In an engine, a cylinder having a plurality of laterally projecting conduits, a connection for each of said conduits, separated supporting arms extending from said connections, a valve rocker lever supported by said arms, and means for operating the lever.
40. 10. In an engine, a cylinder having a plurality of laterally projecting conduits, a bracket at the end of each of said conduits, separated supporting arms extending from said brackets, a valve rocker lever having a pivot pin clamped to said arms, and means 45 for operating said lever.
45. 11. A valve operating mechanism comprising an operating arm, a tappet mounted in the arm, means to prevent turning of the tappet in the arm and an enlarged head upon the tappet having an arcuate face, a cup in which the head of the tappet is seated, the cup being mounted upon the shank of the tappet between the head thereof and the operating arm, and an operating rod extending 50 into the cup and engaging the arcuate face.
55. In testimony whereof I affix my signature.

JESSE G. VINCENT.
